(57) **CLAIM**

The ornamental design for portable loudspeakers, as shown and described.

DESCRIPTION

FIG. 1 is a perspective view of portable loudspeakers that have the design.

FIG. 2 is front elevational view of the portable loudspeakers.

FIG. 3 is a side elevational view of the portable loudspeakers, the opposite side view being a mirror image thereof.

FIG. 4 is a rear elevational view of the portable loudspeakers.

FIG. 5 is a top plan view of the portable loudspeakers; and, FIG. 6 is a bottom plan view of the portable loudspeakers.

The broken line showing on the drawing disclosure is for illustrative purposes only and forms no part of the claimed design.
